DECANTER

Ernest L. Du Pree, Weston, Conn.

Application August 27, 1957, Serial No. 47,519

Term of patent 14 years

(Cl. D58—6)

I claim:

The ornamental design for a decanter, as shown and described.
